CLAIM

The ornamental design for a moving strap, as shown and described.

DESCRIPTION

FIG. 1 illustrates a front perspective view of a moving strap; FIG. 2 illustrates a rear perspective view of the moving strap of FIG. 1;

FIG. 3 illustrates a front perspective view of the moving strap of FIG. 1 worn by a user;

FIG. 4 illustrates a rear perspective view of the moving strap of FIG. 1 worn by the user;

FIG. 5 illustrates a front view of the moving strap of FIG. 1 worn by the user;

FIG. 6 illustrates a rear view of the moving strap of FIG. 1 worn by the user;

FIG. 7 illustrates a left view of the moving strap of FIG. 1 worn by the user; and,

FIG. 8 illustrate right view of the moving strap of FIG. 1 worn by the user.

The in broken lines showing a torso region of a user from FIG. 3 to FIG. 8 illustrate environmental structure only and do not form part of the claimed design. The broken lines shown on the moving strap from FIG. 1 to FIG. 8 represents stitching that does not form part of the claimed design.
